W. H. Reid.

UNITED STATES PATENT OFFICE.

CHARLES HAMMER, OF QUEENS, NEW YORK, ASSIGNOR TO AMERICAN METAL CAP COMPANY, OF BROOKLYN, NEW YORK, A CORPORATION OF NEW YORK.

BAND-LUG CLOSURE.

Application filed January 18, 1922. Serial No. 530,082.

To all whom it may concern:

Be it known that I, CHARLES HAMMER, a citizen of the United States, and a resident of Queens, in the county of Queens and State of New York, have invented certain new and useful Improvements in Band-Lug Closures, of which the following is a specification.

This invention relates to closures for glass containers, the object thereof being to provide an improved combined removable sealing band and a rotatable and reusable closure.

One of the objects of the invention is the provision of a shallow flanged cap having a plurality of projections adapted to engage the projections or threads of a glass container and a removable sealing band cooperating with the cap in such way as to materially extend below the flange thereof and engage directly with a shoulder of the container whereby the cap is securely retained on the container and the package effectively sealed, yet when the sealing band is removed the cap is reusable on the rotation thereof to seal the container during the further use of the contents thereof.

Another object of the invention is the provision of an improved glass container having a special form of multiple threads or projections and a spaced shoulder therebelow whereby a combined shallow flanged cap and sealing band may be effectively used therewith so that the container may be readily sealed and the cap reused upon the removal of the band, and in which the cap and band can be sealed under considerable downward pressure without the cap projections engaging the container shoulder.

In the accompanying drawing illustrating one embodiment of my invention, Fig. 1 is a plan view partially broken away.

Fig. 2 is a partial vertical section of the cap and band before sealing.

Fig. 3 is a partial section showing the sealed package.

Fig. 4 shows the use of the cap after the sealed package has been opened.

This improved closure comprises a metal cap 2 and a sealing band 3 particularly applicable to a glass container such as a jar 4. The cap 2 comprises a top 5 having a

shallow flange or skirt, which is provided at its lower free or raw edge with a plurality of lugs located at intervals therearound and adapted to engage the multiple threads or projections of the container.

The container is provided with a series of separate projections 8, that are inclined and symmetrical, with their extremities preferably tapered as at 9. It will be observed that the inclination of the tapered end at the right hand of each projection or thread of the glass container is somewhat sharper than the inclination of the lower edge of the projection. Below the projections 8 is a rib, shoulder or flange 10 that preferably projects outward further than do the lugs 8, as indicated in Fig. 2. This rib 10 is also located below the projections 8 a sufficient distance to permit the lugs 7 on the cap to slide along the entire lower faces of the projections 8 on the container without being brought into engagement with the rib 10. Heretofore, this rib 10 has been arranged in close proximity to the jar lugs or threads, and this would tend to cause a kind of binding or wedging action of the cap lugs between the projections and ribs on the container.

The band 3 has its upper edge 12 bent over the top of the cap 5, and its lower edge 13 adapted to bend inwardly against the lower wall of the rib 10.

This cap shown has a raw or straight edge that is pressed inwardly at four points to form the lugs 7.

It will be further observed that the projections 8 on the container or jar do not overlap at their adjacent ends, but are spaced apart or separated in a vertical direction. This will facilitate the application of the cap, as the lugs 7 can pass freely down between the spaced ends of the threads by a simple vertical movement with practically no turning of the cap.

It will be further understood that the lugs on the cap are arranged relative to the inclined threads 8 so that in the subsequent use the lugs will engage the lower faces of each thread to draw the cap with its liner 14 down on the jar as indicated in Fig. 4. When the cap is first applied the lug will be

located in the comparatively wide space between each thread 8 and the rib 10 so that it is free to be forced downwardly by pressure on top of the cap in the operation of sealing the band.

When the closure is applied, as stated, the cap is put on and the lug passed between the ends of the threads, and the cap seated on top of the jar. Thereupon the band 3 is applied, so that its bent top edge 12 will engage the top 2 at the outer portion as indicated in Fig. 2. This will bring the lower portion 13 of the band below the rib 10, and while pressure is still applied on the upper flange 12 of the band in a downward direction, the lower portion 13 is bent inwardly against the lower wall of the rib 10, as shown in Fig. 3. This will cause a very strong and tight seal of the closure on the container. The band may have lapping ends in the form of a tongue 15, that may have another tongue 16 projecting through a slot in the other tongue, that will hold the band together at the ends but permit easy removal by bending back the two tongues.

When it is desired to have access to the container, the band is loosened and removed and this will leave the lug closure free for removal. The lug cap can now be returned to the container if only partially used, and can be reused a number of times by simply screwing the lugs down firmly under the thread portions 8.

From the foregoing it will be seen that the skirt or flange of the cap is of just sufficient height or depth to overlap the threads of the glass container so that the cap can be made with a shallow flange or skirt while the sealing band is of such depth or height that it will overlap the shallow flange or skirt and will also extend beyond the same and overlap the shoulder or rib on the glass container and that furthermore the shallow flange is of just such depth as will enable its lugs to pass under the glass threads of the container and effectively pass therebetween and the shoulder or rib on the container, which latter projects sufficiently beyond the glass threads to enable the overlapping sealing band to engage the same on its outer wall and to be bent under the same in an effective manner to hold the cap in place. Furthermore by reason of the space between the ends of the glass threads the cap can be efficiently pressed down without turning it when the sealing band is applied and this effective sealing is also obtained even though the cap may be somewhat turned by reason of the sharp inclination at the ends of the threads since the effective drawing down of the cap is largely obtained by the long gradual inclination at the under side of the glass threads. Thus by this construction I am able to provide a combined shallow flanged rotatable cap capable of ready re-use, and a seal-

ing band which will effectively hold the cap on the container and seal such container by overlapping both the cap and the jar below the shallow flange of the cap so that the band can be effectively turned under 70 and engage the glass shoulder of the jar itself and I believe that I am the first to provide a combined shallow flanged cap and sealing band of substantially twice the height of the cap; in other words a combined rotatable cap and sealing band which is effective to overlap the entire skirt of the cap and extend such distance therebeyond as to overlap also a portion of the glass container and be secured by being bent so as to 80 directly engage under the shoulder of such container. The construction also permits the use of a shallow flange cap which materially results in a saving of metal and also enables the use of a glass container having 85 a neck of less height.

I also believe that I am the first to provide a sealed package in which the structure is such that vertical movement in one direction during the operation of sealing the band 90 under the shoulder and without the necessity of rotating the cap is permitted. Aside from the other advantages hereinbefore set forth it will be seen that this improved package enables the user to readily determine 95 whether the sealed package has been tampered with or not.

Moreover it will be observed that the sealing band and cap so cooperate that the sealing band forms the first or primary locking 100 means for the cap without any substantial rotation thereof during the first application of the cap to the container, while the projections of the cap form the second or secondary locking means on the removal of 105 the band, and which is effected by then rotating the cap. That while the present improvement is particularly well adapted for shallow flanged caps, it of course could be used with skirts or flanges of greater depth 110 if found desirable, and therefore it is to be understood that by describing in detail herein any particular form, structure or arrangement, it is not intended to limit the invention beyond the terms of the several claims 115 or the requirements of the prior art.

What I claim is:

1. A combined rotatable and reusable metal cap and sealing band, said cap comprising a top having a depending flange or skirt provided with inwardly extending locking projections, said skirt having its lower edge terminating an appreciable distance above the line of contact of said band with the neck of the receptacle to be closed 120 and said sealing band extending an appreciable distance below said flange with its lower portion in position to be bent inwardly to directly engage under a shoulder of the receptacle, said sealing band and cap 125

so cooperating that the sealing band forms the first locking means for the cap without the rotation thereof while the projections of the cap form the second locking means on the removal of the band.

2. A combined rotatable and reusable metal cap and sealing band, said cap comprising a top having a depending flange or skirt provided with inwardly extending locking projections, said skirt having its lower edge terminating an appreciable distance above the line of contact of said band with the neck of the receptacle to be closed and said sealing band extending an appreciable distance below said flange with its lower portion in position to be bent inwardly to directly engage under a shoulder of the receptacle, and with its upper portion in position to overlap the top of the cap, said sealing band and cap so cooperating that the sealing band forms the first locking means for the cap without the rotation thereof while the projections of the cap form the second locking means on the removal of the band.

3. The combination with a container having a plurality of projections and a shoulder spaced therebelow, of a combined rotatable and reusable metal cap and sealing band, said cap comprising a top having a depending shallow flange or skirt terminating adjacent to the under side of said projections and providing with inwardly extending locking projections, said sealing band extending below the skirt and terminating adjacent to the under side of the shoulder and adapted to have its top and bottom edges bent inwardly, its bottom edge directly engaging the shoulder of the container thereunder, said sealing band and cap so cooperating that the sealing band forms the first locking means for the cap without the rotation thereof while the projections of the cap form the second locking means on the removal of the band.

4. The combination with a container having a plurality of projections and a shoulder spaced therebelow, of a combined rotatable and reusable metal cap and sealing band, said cap comprising a top having a depending flange or skirt and provided with inwardly extending locking projections, said sealing band overlapping the skirt and having substantially twice the depth of said skirt and terminating adjacent to the under side of the shoulder and having its top inwardly bent to engage the cap and its lower portion inwardly, bent directly under the shoulder of the container, said sealing band and cap so cooperating that the sealing band forms the first locking means for the cap without the rotation thereof while the projections of the cap form the second locking means on the removal of the band.

5. The combination with a container pro-

vided with a threaded neck and a spaced shoulder therebelow, of a combined rotatable and reusable metal cap and sealing band, said cap comprising a top having a depending shallow flange or skirt having a free edge terminating adjacent to the under side of said threads and provided with inwardly extending locking projections at its free edge, said sealing band having substantially twice the depth of the skirt and extending below the same and terminating adjacent to the under side of the shoulder and having its top portion bent over the top of the cap and its bottom portion bent inward directly to engage the shoulder thereunder, said sealing band and cap so cooperating that the sealing band forms the first locking means for the cap without the rotation thereof while the projections of the cap form the second locking means on the removal of the band.

6. A sealed package comprising a container having a single row of projections or threads with the ends spaced apart, a rotatable and reusable metal cap comprising a top having a depending flange or skirt provided with inwardly extending locking projections, each of a length adapted to pass between the spaced ends of a pair of threads, said container having a shoulder spaced below said threads, and a sealing band, the structure of the threads and projections being such as to permit vertical movement of the cap projections in one direction during the operation of sealing the band under the shoulder.

7. A sealed package comprising a glass container having a single row of projections or threads with the ends spaced apart, each having a long inclined lower edge in the direction of its length terminating in a more sharply inclined upper end, and having a shoulder spaced below said threads, the space below the sharply inclined upper end and the shoulder being greater than that between the major part of the lower edge of the thread and said shoulder, a rotatable and reusable metal cap comprising a top having a depending flange or skirt provided with inwardly extending locking projections, each of a length adapted to pass between the spaced ends of a pair of threads, and a sealing band, the structure of the threads and projections being such as to permit vertical movement of the cap projections in one direction during the operation of sealing the band under the shoulder.

8. A sealed package comprising a container having a single row of projections or threads with the ends spaced apart, a rotatable and reusable metal cap comprising a top having a depending shallow flange or skirt provided with inwardly extending locking projections, each of a length adapted to pass between the spaced ends of a pair

of threads, said container having a shoulder spaced below said threads, and a sealing band, the construction of the threads and projections being such as to permit vertical movement of the cap projections in one direction during the operation of sealing the band under the shoulder.

9. The combination with a container having a plurality of lengthwise spaced threads or projections and a shoulder spaced therebelow, of a combined sealing band and rotatable and reusable metal cap having a depending shallow skirt or flange provided with inwardly extending locking projections, each of a length adapted to pass between the spaced ends of a pair of projections, said sealing band extending below the skirt and having its top and bottom portions adapted to be bent inwardly, its bottom portion directly engaging the shoulder of the container thereunder, the structure of the threads and projections being such as to permit vertical movement of the cap projections in one direction during the operation of sealing the band under the shoulder.

10. A combined rotatable and reusable metal cap and sealing band, said cap comprising a top having a depending flange or skirt provided with inwardly extending locking projections, each of a length adapted to pass between the ends of a pair of lengthwise spaced threads or projections of a container having a shoulder spaced below said threads, the structure of the threads and cap projections being such as to permit vertical movement of the cap and its projections in one direction during the operation of sealing the band under the shoulder.

40 11. The combination with a container, of a cap therefor, means for attaching the cap to the container, and a second attaching means inoperative during the positioning and attachment of the cap by said first mentioned attaching means.

12. The combination with a container, of a cap therefor, means to attach the cap to the container, said cap being so constructed that it may be brought by a straight downward movement into position to be attached by said means, and a second attaching means inoperative during the positioning and attachment of the cap by said first attaching means.

55 13. The combination with a container, of a cap therefor, means to attach the cap to the container, said cap being so constructed that it may be brought by a straight downward movement into position to be attached by said means, and a second attaching means inoperative during the positioning and attachment of the cap by said first attaching means, said second attaching means being brought into operative position by a rotative movement of the cap on the container.

14. The combination with a container, of a cap therefor, means for attaching the cap to the container, and a second attaching means inoperative during the positioning and attachment of the cap by said first mentioned attaching means, said first mentioned attaching means comprising a sealing band removable from the body of the cap for detaching the cap from the receptacle.

15. The combination of a jar having a ledge disposed below its mouth, said jar having projections between said ledge and the mouth of the jar, a cover having means adapted to engage said projections whereby the cover may be turned onto and off from said jar thus forming a reclosure for the jar, and a sealing band adapted to engage a portion of the cover and be turned underneath said ledge for drawing said cover into sealing contact with the jar, said band having means whereby it may be readily removed as a seal from the jar, the disposition of the said projections and means being such as to permit the closure to be brought into sealing contact with the jar without interference by or functional action of the said projections and means during the application of the sealing band.

16. The combination of a jar having a ledge disposed below its mouth, said jar having projections between said ledge and the mouth of the jar, a cover having means adapted to engage said projections whereby said cover may be turned onto and off from said jar thus forming a reclosure for the jar, and a sealing band having an inwardly projecting flange adapted to overlie a portion of the cover, said sealing band being adapted to be turned underneath said ledge for drawing down said cover into sealing contact with the jar, said band having means whereby it may be readily removed as a seal from the jar, the disposition of the said projections and means being such as to permit the closure to be brought into sealing contact with the jar without interference by or functional action of the said projections and means during the application of the sealing band.

17. The combination of a jar having a ledge disposed below and parallel with its mouth, said jar having a thread between said ledge and the mouth of the jar, a cover having means adapted to engage said thread whereby said cover may be turned onto and off from said jar thus forming a reclosure for the jar, and a sealing band having an inwardly projecting flange adapted to overlie a portion of the cover, said sealing band being adapted to be turned underneath said ledge for drawing the cover into sealing contact with said jar, said band having means whereby it may be readily removed as a seal from the jar, the disposition of the said

projections and means being such as to permit the closure to be brought into sealing contact with the jar without interference by or functional action of the said projections and means during the application of the sealing band.

18. The combination with a container, of a cap therefor comprising an attaching means by which the cap is originally attached to the container, said attaching means being separable from the body of the cap to permit removal of the cap, a second attaching means by which the cap may be attached to the container after the original attaching means has been removed, said second attaching means being maintained out of attaching position during the original positioning and attachment of the cap to the container.

19. The combination with a container, of a cap therefor comprising an attaching means by which the cap is originally attached to the container, said attaching means being separable from the body of the cap to permit removal of the cap, a second attaching means by which the cap may be attached to the container after the original attaching means has been removed, said second attaching means comprising interlocking parts carried by the cap and container respectively and maintained out of interlocking relation during the original positioning and attachment of the cap to the container.

20. The combination with a container, of a cap therefor comprising an attaching means by which the cap is originally attached to the container, said attaching means being separable from the body of the cap to permit removal of the cap, a second attaching means by which the cap may be attached to the container after the original attaching means has been removed, said second attaching means comprising interlocking surfaces on the cap and container respectively, said surfaces being held out of engagement during the original placing and attachment of the cap to the container and brought into operative relation by a rotative movement of the cap on the container.

21. The combination of a container comprising a neck, a closure cap therefor comprising a flange portion extending downward to surround the neck, means for originally securing the cap in position, a second securing means for holding the cap in position on the container after it has been removed, said second securing means comprising interengaging projections on the cap and container respectively, said projections being arranged to be held out of contact during the original placing and securing of the cap on the container.

22. The combination with a container, of a cap therefor, means for attaching the cap to

the container, and a second attaching means maintained out of operative position during the positioning and attachment of the cap by said first mentioned attaching means.

23. The combination with a container, of a cap therefor, means to attach the cap to the container, said cap being so constructed that it may be brought by a straight downward movement into position to be attached by said means, and a second attaching means maintained out of attaching position during the positioning and attachment of the cap by said first attaching means.

24. The combination with a container, of a cap therefor, means to attach the cap to the container, said cap being so constructed that it may be brought by a straight downward movement into position to be attached by said means, and a second attaching means maintained out of attaching position during the positioning and attachment of the cap by said first attaching means, said second attaching means being brought into operative position by a rotative movement of the cap on the container.

25. The combination with a container, of a cap therefor, means for attaching the cap to the container, and a second attaching means maintained out of operative position during the positioning and attachment of the cap by said first mentioned attaching means, said first mentioned attaching means comprising a part removable from the body of the cap for detaching the cap from the receptacle.

26. A container adapted to be sealed by a rotatable and reusable cap and sealing band and having a shoulder and a single row of non-overlapping threads or projections located wholly substantially midway between the shoulder and the top of the container with their proximate ends spaced apart sufficiently to enable the passage therebetween of cap projections, each of said threads having a relatively long, straight, inclined lower edge terminating at its upper end in a relatively short, sharp, inclined lower edge thereby materially increasing the space between said sharp end and the shoulder, as compared with the space between the major part of the thread and the shoulder, for the reception of a cap projection, whereby the ends of the threads may be in close non-overlapping proximity, said thread functioning to permit the rotatable cap to be initially positioned adjacent to said sharp end to prevent its jumping off during the application of the sealing band, and then sealed under downward pressure by the sealing band without engagement of the locking projections of the cap with the threads or shoulder of the container, and then to be subsequently sealed on the removal of the sealing band by the rotation of the cap to have its projections engage under the long,

100

- inclined edge of the container thread, whereby said sealing band forms the first locking means and the cap projections the second locking means on the removal of the band.
- 5 27. A container adapted to be sealed by a rotatable and reusable cap and sealing band and having a shoulder and a single row of non-overlapping threads or projections located wholly substantially midway between the shoulder and the top of the container with their ends spaced apart sufficiently to enable the passage therebetween of cap projections, said shoulder projecting beyond the threads, each of said threads having a relatively long, straight, inclined lower edge terminating at its upper end in a relatively short, sharp, inclined lower edge thereby materially increasing the space between said sharp end and the shoulder, as compared with the space between the major part of 10 the shoulder and the top of the container with their ends spaced apart sufficiently to enable the passage therebetween of cap projections, each of said threads having a relatively long, straight, inclined lower edge terminating at its upper end in a relatively short, sharp, inclined lower edge thereby 15 materially increasing the space between said sharp end and the shoulder, as compared with the space between the major part of the thread and the shoulder, for the reception of a cap projection, whereby the ends of the threads may be in close non-overlapping proximity, said thread functioning to permit the rotatable cap to be initially positioned adjacent to said sharp end to prevent 20 its jumping off during the application of the sealing band, and then sealed under downward pressure by the sealing band without engagement of the locking projections of the cap with the threads or shoulder of the container, and then to be subsequently 25 sealed on the removal of the sealing band by the rotation of the cap to have its projections engage under the long, inclined edge of the container thread, whereby said sealing band forms the first locking means and the cap projections the second locking means 30 on the removal of the band.
- 35 40. sealing band forms the first locking means
- and the cap projections the second locking means on the removal of the band.
28. A container adapted to be sealed by a rotatable and reusable cap and sealing band and having a shoulder, and a single row of non-overlapping threads or projections located wholly substantially midway between the shoulder and the top of the container with their ends spaced apart sufficiently to enable the passage therebetween of cap projections, said shoulder projecting beyond the threads, each of said threads having a relatively long, straight, inclined lower edge terminating at its upper end in a relatively short, sharp, inclined lower edge thereby 45 materially increasing the space between said sharp end and the shoulder, as compared with the space between the major part of the thread and the shoulder, for the reception of a cap projection, whereby the ends of the threads may be in close, non-overlapping proximity, said thread functioning to permit the rotatable cap to be initially positioned adjacent to said sharp end to prevent 50 its jumping off during the application of the sealing band, and then sealed under downward pressure by the sealing band without engagement of the locking projections of the cap with the threads or shoulder of the container, and then to be subsequently 55 sealed on the removal of the sealing band by the rotation of the cap to have its projections engage under the long, inclined edge of the container thread, whereby said sealing band forms the first locking means and the cap projections the second locking means 60 on the removal of the band.
